UNITED STATES PATENT OFFICE

2,424,381

DOOR LOCKING AND CLOSING DEVICE

Wilfred A. Beauchamp, Chicago, Ill., assignor to
The Youngstown Steel Door Company, Cleve-
land, Ohio, a corporation of Ohio

Application May 13, 1943, Serial No. 486,823

5 Claims. (Cl. 292—283)

1

This invention relates to door locking and closing devices. This invention has for an object the association of locking and closing devices for sliding car doors whereby to secure a reduction in the number of parts together with a decrease in weight and cost and a reduction in the expense of application.

A further object is to provide a door locking and closing device which permits disposition of a closing lever so that it is more easily operable.

A further object is to provide a door locking and closing device for sliding car doors embodying a lock bracket and a tapered locking pin and means carried by the lock bracket for limiting upward movement of the pin.

A further object is to provide a door locking and closing device embodying a hasp and a lock bracket wherein the hasp is constructed to cooperate with locking means carried by the bracket to lock the door and with a horizontally positioned lever also carried by the bracket to impart closing movement to the door.

Other objects of the invention will become clear as the description thereof proceeds.

In the drawings forming part of this specification:

Fig. 1 is a fragmentary elevation showing a device embodying the instant invention applied to a railway box car, the device being illustrated in door locking position.

Fig. 2 is a view similar to Fig. 1, showing the door partly open and parts of the device engaged to impart closing movement to the door.

Fig. 3 is a horizontal section taken on line 3—3 of Fig. 1 looking in the direction of the arrows.

Fig. 4 is a horizontal section taken on line 4—4 of Fig. 1 looking in the direction of the arrows.

Fig. 5 is a vertical section taken on line 5—5 of Fig. 1 looking in the direction of the arrows.

Fig. 6 is a vertical section taken on line 6—6 of Fig. 1 looking in the direction of the arrows.

Referring to the drawings which illustrate a preferred embodiment of the invention, numeral 10 designates a portion of the side wall of a railway box car which is provided with a door opening 11 defined by means of door posts, one of which is partially shown at 12. The side wall 10 also embodies metallic sheathing 13 secured to the door post 12, as illustrated in Fig. 3 of the drawings. A front stop 14 is also secured to the door post 12.

The door opening 11 is adapted to be closed by means of a sliding door 15 which may be of any desired construction but which, as best illustrated in Figs. 1 to 3, inclusive, of the drawings, embodies a metallic panel 16 formed with a plu-

2

rality of horizontal corrugations 17. Adjacent each vertical margin of the door the metallic panel is offset outwardly, as indicated at 18, to provide a flange 19 substantially parallel to the main plane of the panel. The vertical margins of the door are reinforced and, as best illustrated in Fig. 3 of the drawings, the reinforcement for the front vertical margin of the door is obtained by means of a substantially Z-shaped reinforcing member 20 which overlaps the flange 19 of the metallic panel and is secured thereto in any desired manner. The reinforcement for this margin of the door is completed by means of a backing plate 21 which is secured to the panel 16 inwardly of the offset portion 18 as by means of rivets 22 and to the reinforcing member 20 as by means of rivets 23. The front stop 14 is adapted to limit closing movement of the door by engagement to the vertical reinforcing member 20.

The door is adapted to be locked in its closed position by means of a locking and closing device embodying the instant invention. This device embodies a hasp fastener 24 preferably disposed upon and secured to one of the horizontal corrugations 17 as by means of rivets 25. The hasp fastener is reinforced by means of a reinforcing member 26 lying within the horizontal corrugation 17 and secured thereto by means of the rivets 25. The hasp fastener 24 extends through an eye 27 formed in a hasp or locking member 28 so as to swingably support the hasp. The hasp is provided with a box section 29, as best illustrated in Fig. 3 of the drawings, through which a tapered pin or locking element 30 is adapted to extend in order to lock the door.

The pin 30 is carried by a lock bracket 31 secured to the car side adjacent to the door opening 11 as by means of rivets 32. The lock bracket 31, which preferably is in the form of a casting, is formed with vertically spaced housing members 33 and 34 which slidably receive the tapered pin 30. In locking position, as more clearly shown in Fig. 1 of the drawings, the straight edge 35 of the tapered pin 30 bears against the sides of the housing members 33 and 34 and the inclined edge 36 of the tapered pin assumes locking engagement with a correspondingly tapered wall 37 of the box section of the hasp.

As best shown in Figs. 1 and 2 of the drawings, the upper portion of the tapered pin 30 is reduced in width so as to provide a shoulder 38 extending inwardly from the tapered edge 36 of the pin. The upper housing member 33 is formed with spaced ears 39 and 40 between which a catch 41 is swingably secured as by means of a rivet 42.

The swinging catch 41 lies in the plane of the tapered pin 30 and comprises a nose portion 43 adapted to lie vertically above the shoulder 38 of the pin when the latter is in locking position and a finger grip portion 44 provided with an opening 45 by means of which the catch can be operated. The finger grip portion over-balances the nose 43 so as to bias the latter into overlapping relationship with the shoulder 38 on the tapered pin.

As appears from Fig. 1 of the drawings, overlapping relationship between the shoulder 38 and the nose 43 of the swinging catch is provided for as soon as the tapered pin extends sufficiently below the lower housing member 34 to permit a seal (not shown) to be threaded through aligned seal receiving openings 46 and 47 formed respectively in the lower portion of the pin and in the lock bracket. It is apparent that the swinging catch will prevent the pin from moving upwardly to such an extent that the seal may be sheared. However, in the event that the pin is in the position described immediately above and the door is not fully closed, it is possible for the door to move in closing direction and the tapered pin to drop by the action of gravity to take up the clearance created by the closing movement of the door while preventing return opening movement of the door. The dropping of the pin is not interfered with by the swinging catch 41 which is in position to effectively prevent accidental upward movement of the pin to an extent which might result in shearing of the seal. It will be clear, moreover, from the showing of Figs. 1 and 2 of the drawings that irrespective of the position of the pin when it is out of locking engagement with the hasp, the pin can, without interference from the swinging catch, be dropped through the housing members and automatically assume the relationship with the catch as illustrated in Fig. 1 of the drawings so that manual manipulation of the catch is unnecessary.

In addition to the foregoing function of the illustrated device of the instant invention, it serves as well to impart closing movement of the door. For this purpose the hasp 28 is provided with an extension 48 reinforced by means of a rib 49. The extension is formed with a plurality of shoulders 50 which extend downwardly so as to be capable of selective engagement by an upstanding lobe 51 formed on a horizontally positioned lever 52.

The lever 52 is swingably supported between a pair of ears 53 and 54 extending from the lower housing member 34 of the lock bracket. The swingable support is obtained by means of a rivet 55 extending through the ears 53 and 54. In accordance with the instant invention the lever is arranged so that it lies horizontally and to insure this position of the lever it is formed with a projection 56 adapted to engage the underside of the housing member 34.

The operation of the locking feature of the closing and locking device has been described hereinabove. In order to close the door when it is in partially open position, as for example, the position illustrated in Fig. 2 of the drawings, the hasp 28 is disposed so that it is supported upon the lower housing member 34. The lever 52 is then swung in clockwise direction until engagement between the upstanding lobe 51 on the lever and one of the shoulders 50 on the hasp is obtained. The lever 52 is then easily swung in counter-clockwise direction since it is pulled downwardly and during this movement of the le-

ver the door is moved in closing direction. If at this time the door is not fully closed, the operation described above is repeated by engaging the upstanding lobe 51 with another of the shoulders 50 and this process is continued until the door is closed. When this has occurred, the pin is dropped through the lower housing member and sealed. As soon as the shoulder 38 on the pin passes below the nose 43 of the pivoted catch 41, the latter automatically swings in counter-clockwise direction so as to position the nose 43 vertically above the shoulder 38 and thereby prevent accidental upward movement of the pin and possible shearing of the seal.

During the operation of the lever to effect closing movement of the door engagement of the lever with the shoulders 50 on the hasp is insured by the reinforcing rib 49 which prevents the hasp from swinging outwardly.

As shown in Fig. 1 of the drawings pin 30 is in the uppermost door locking position which will permit sealing of the door and lever 52 is horizontal. If because of normal discrepancies of car construction as, for example, a door opening which is too wide, or a door which is too narrow, the door is not fully closed when the pin, hasp and lever are in the position shown in Fig. 1, the door may move in closing direction. Upon such movement, the pin will drop and re-establish engagement with the hasp as is well known. This action can continue until reinforcing member 28 is in contact with front stop 14.

At the beginning of this movement of the door, the lever 52 is horizontal and in engagement with the innermost shoulder 50. It is clear, however, from the construction of the hasp and its relationship with the lever that the lever when in horizontal position will not impede the movement of the hasp with the door. Similarly, if the lever should not be in horizontal position when the door is locked and sealed, closing movement of the door can occur without hindrance from the lever.

It will be apparent that numerous changes and modifications in the details of the invention will be clear to those skilled in the art. It is intended, therefore, that all such modifications and changes be comprehended within this instant invention, which is to be limited only by the scope of the claims appended hereto.

I claim:

1. In a locking and closing device for sliding car doors having a swingably supported hasp and a lock bracket provided with vertically spaced housing members slidably receiving a pin adapted to have locking engagement with said hasp, the combination comprising spaced ears extending from the lower of said housing members, a lever pivotally mounted between said ears in offset relation to said pin, means on said lever engaging said lower housing member to maintain said lever in substantially horizontal position, an extension on said hasp beyond the point of engagement of said hasp and pin, and a shoulder on said extension, said lever being engageable with said shoulder and operable to exert a pull upon said hasp, for the purpose set forth.

2. In a locking and closing device for sliding car doors having a swingably supported locking member and a lock bracket carrying locking means adapted to have engagement with said locking member, the combination comprising a lever pivotally mounted on said lock bracket in offset relation to said locking means, means on said lever engaging said lock bracket to maintain

said lever in substantially horizontal position, an extension on said locking member beyond the point of engagement of said locking member and locking means, and a shoulder on said extension, said lever being engageable with said shoulder and operable to exert a pull upon said locking member, for the purpose set forth.

3. In a locking and closing device for sliding car doors having a swingably supported hasp and a lock bracket carrying a vertically slidable pin adapted to have locking engagement with said hasp, the combination comprising a lever pivotally mounted on said bracket in offset relation to said pin, means on said lever engaging said bracket to maintain said lever in substantially horizontal position, an extension on said hasp beyond the point of engagement of said hasp and pin, and a shoulder on said extension, said lever being engageable with said shoulder and operable to exert a pull on said hasp, for the purpose set forth.

4. In a locking and closing device for sliding car doors having a swingably supported hasp and a lock bracket provided with vertically spaced housing members slidably receiving a tapered pin adapted to have locking engagement with said hasp, the combination comprising spaced ears extending from the lower of said housing members, a lever pivotally mounted between said ears in offset relation to said pin, means on said lever engaging said lower housing member to maintain said lever in substantially horizontal position, an extension on said hasp beyond the point of engagement of said hasp and pin, and a shoulder on said extension, said lever being engageable with said shoulder and operable to exert a pull upon said hasp, said hasp when in locking engagement with said pin being capable of movement relative to said lever in the direction of pull upon said hasp when said lever is in horizontal

5 40

position and in engagement with said shoulder, said relative movement being also capable of occurring in positions of said lever other than when said lever is in horizontal position and in engagement with said shoulder.

5. In a device of the character described for sliding car doors comprising a hasp fastener, a hasp swingably supported by said fastener, a lock bracket, vertically spaced housing members on said bracket, said hasp lying between said housing members substantially horizontally when in locking position, a tapered locking pin slidably received in said housing members, said pin being adapted to have locking engagement with said hasp, a portion of said pin being reduced in width to provide a shoulder, spaced ears on the upper of said housing members, and a catch pivotally supported between said ears, said catch lying substantially in the plane of said pin and being engageable with said shoulder when said pin is in locking position, said pin when disengaged from said hasp being engageable with said catch to displace said catch and prevent it from interfering with movement of the pin into locking engagement with said hasp.
